FOREIGN PATENT DOCUMENTS

EP	2639144	9/2013
FR	2764261	12/1998

Primary Examiner — Philip S Hyder*Assistant Examiner* — Darlington Ly(74) *Attorney, Agent, or Firm* — Norton Rose Fulbright
Canada LLP(57) **CLAIM**

The ornamental design for a bicycle handlebar, as shown and described.

DESCRIPTION

FIG. 1 is a right rear perspective view of a bicycle handlebar in accordance with our new design.

FIG. 2 is a left front perspective view of the design of FIG. 1.

FIG. 3 is a top plan view of the design of FIG. 1.

FIG. 4 is a front elevational view of the design of FIG. 1.

FIG. 5 is a rear elevational view of the design of FIG. 1.

FIG. 6 is a left side elevational view of the design of FIG. 1; and,

FIG. 7 is a right side elevational view of the design of FIG. 1. The broken line showing of the bicycle is for the purpose of illustrating environmental structure and forms no part of the claimed design.
